POWDER-SPRAYING APPLIANCE

Svend Bramsen, Fritz Wahlin, and Eric Gustafson, Chicago, Ill., assignors to Binks Manufacturing Company, Chicago, Ill., a corporation of Delaware

Application June 29, 1933, Serial No. 678,220

17 Claims. (Cl. 91—8)

Our invention relates to a pneumatically actuated appliance forcing powdered or otherwise comminuted dry materials out of a container and thereafter projecting this material in the form of an effectively directed spray against a surface which is to be coated with a layer of such material.

In one of its general objects, our invention aims to simplify the procedure required for applying a dry and finely subdivided material to a surface and of greatly simplifying and cheapening the needed apparatus, in comparison with the procedure and apparatus heretofore employed for such purposes. Furthermore, our invention aims to provide a simple, light and easily portable container and spray device assembly for the above purpose which can readily be adjusted according to the nature of the material, and which will also permit the projected spray to be easily varied from a circular cross-section to that of a flattened or sheet-like spray.

In using small particles of material as constituents of a coating which is adhesively attached to a surface, it has heretofore been customary (on a large manufacturing scale) to drop such particles of material loosely upon a substantially horizontal surface after applying a thin layer of an adhesive liquid (such as a varnish or glue) to that surface, and to brush or shake off the surplus of material later on. With soft materials, such a brushing usually roughens part of the surface, so that the coating may need to be rolled or pressed down later to secure a uniform appearance; and for many purposes it is necessary to pass the material through an oscillating sieve for securing the desired distribution of its particles, thereby also requiring an additional operation and a correspondingly complicated equipment.

Moreover, dry material cannot readily be distributed with any degree of uniformity over interior surfaces of an object, as for example upon the inner faces or sides of a suit-case, violin case or the like. And a subsequent smoothing of the coating is not readily feasible upon surfaces which are not flat, nor can any such additional smoothing operation be employed when the coating is to have a roughened or pebbled appearance.

Another procedure which has also been employed with many materials consists in simultaneously projecting both particles of the material and an adhesive against the surface. This procedure either requires two separate projecting nozzles with a separate supply of air to each, or else requires some arranging for intermingling the material with the adhesive either before the joint

projection of both thereof or otherwise before both the material particles and the adhesive reach the surface. In either case, these particles of material then are coated (either partly or entirely) with adhesive, so that the resulting coating has a more or less glossy appearance which is undesirable for many purposes, and the amount of adhesive is far greater than the quantity actually needed for causing the particles of material to adhere to each other and to the surface which is to be coated.

Our present invention aims to overcome the above recited objections to the previous procedures and apparatus by providing means whereby compressed air will first loosen and separate particles of dry material within a container, and thereafter will forcibly project these particles in generally non-contiguous relation to each other and in the form of a spray of sufficient concentration for effective direction against the surface which is to be coated; and whereby the pressure of the air projected along with these particles will also press such particles firmly against a still liquid adhesive layer on the said surface and will expedite the drying of the adhesive.

More particularly, our invention aims to provide a material-spraying appliance for this purpose constructed so as to constitute a cover for a receptacle containing the material, and aims to provide an appliance construction which will be exceedingly simple, inexpensive, non-clogging, and easily manipulated. In addition, our invention aims to provide means whereby such an appliance can readily be adjusted for efficient use with materials of widely varying specific gravity and compressibility, and aims to provide an easily cleaned appliance which can readily be manipulated as a unit by a single hand of the user.

Illustrative of our invention and of more detailed objects of the same.

Fig. 1 is a vertical and generally diametric section through an embodiment of our invention in which the container is of the so called Mason jar type, and which includes convenient means for adjusting the proportion of the ejected material to the air projected with this material.

Figs. 2 and 3 are fragmentary front and side elevations, respectively, of the part of our appliance attached to the body of the jar or receptacle.

Fig. 4 is a fragmentary plan view of the cast body of the part of our appliance attached to the jar body to serve as a cover.

Fig. 5 is an enlarged axial section through the

body of the main air control valve, taken along the line 5—5 of Fig. 1.

Fig. 6 is a section similar to the upper portion of Fig. 4, showing a simplified form having no means for varying the proportion of the ejected air to that of the projected material.

Fig. 7 is a fragmentary bottom view of the main portion of the receptacle-cover and adjacent parts of Fig. 6.

10 Fig. 8 is an enlarged section taken along the line 8—8 of Fig. 6.

Fig. 9 is a fragmentary central, vertical and longitudinal section through the cast body of the same appliance, taken along the line 9—9 of 15 Fig. 7.

Fig. 10 is a section allied to an upper portion of Fig. 1, showing our spray appliance as further developed for use in projecting the finely divided material either in the form of a conical 20 spray or with the projected spray flattened to a desired and easily regulated extent.

Fig. 11 is a plan view of the same, with the container omitted.

Fig. 12 is an enlarged horizontal section, taken 25 along the line 12—12 of Fig. 10.

Generally speaking, we accomplish the objects of our invention by providing a generally closed and normally upright receptacle for the material; by admitting a jet of compressed air into 30 this container in such a direction as to agitate, whirl and lift the material; by also blowing another jet of air across and above the mouth of the receptacle toward an outlet nozzle to suck the mixture of air and air-separated material toward 35 the said nozzle; by forming the cover of the container so as to cooperate in guiding the material toward the said nozzle; and by providing control valves which can easily be manipulated by the user.

40 In the triple valve form shown in Figs. 1 to 4, designed for projecting the material in a conical mass spray, the receptacle 1 is a glass jar having the usual exterior thread T on its mouth portion. this jar being preferably of glass so that both the 45 amount of material in the jar and the movement of the material in the jar can readily be seen. Screwed upon the mouth end of this jar and normally sealed to it by a compressible gasket 2 is a cast body which includes a cover 3, a tubular shank 4 extending rearwardly from this cover, and a hollow handle 5 depending from the outer 50 end of the shank 4.

The cover 3 has at its forward edge an internally threaded bore 6 in axial alignment with the 55 bore 4A of the tubular shank 4, into which bore a projecting nozzle or outlet nozzle 7 is screwed, and an air nozzle 16 is screwed into the forward end of the said bore 4A, which latter bore desirably has its axis at right angles to the axis A of the jar 1. This shank bore 4A is connected at its 60 rear end to the bore 5A of the handle, and compressed air is supplied to the lower end of the handle bore through an air hose H connected to the handle by a nipple 9, the passage of air from 65 the handle bore to the shank bore 4A being controlled by an air valve including a finger-piece F which can be manipulated by a finger of the hand grasping the handle.

Extending downwardly into the cover 3 is a 70 valve bore 10 which crosses the bore 4A so as to present a downwardly closed valve bore portion 10A below the said bore 4A for receiving the tip of an air valve 11 threaded into the said valve bore 10.

75 The bore 4A is further crossed behind the said

valve bore 10 by a second valve bore 12 which extends entirely through the cover or cap 3 and which desirably is continued downwardly by a tube 13, admission of air from the main horizontal bore 4A to this tube 13 being controlled by 5 a second valve 14. This tube 13 has its downwardly directed outlet at a considerable distance rearwardly from the axis A of the glass jar, and also desirably has its lower portion upright, thereby permitting it to direct a jet of air downwardly 10 in an approximately vertical direction. Moreover, we dispose the tube 13 with its lower end above the midheight of the receptacle, so that its discharge end is entirely above the material when the receptacle is not more than half filled 15 with material. This we do for the reason that initially closely packed material would unduly reduce the agitating and lifting action of the air issuing from this tube if the tube extended down into the material. 20

When all three of the valves are at least partly open, part of the compressed air flowing forwardly through the air passage 4A issues downwardly into the jar so as to loosen and agitate any finely divided material M in the jar. With 25 this air directed in a jet J considerably behind the jar axis A, the resulting agitation will move the material largely in the general direction of the dotted line D in Fig. 1, namely forwardly in the lower portion of the jar and thereafter upwardly. At the same time, a blast of air will also issue forwardly from the air nozzle 16 and through the bore 8A of the discharge nozzle to blow material which is in front of the former nozzle through the latter nozzle and to project this 30 material forcibly through the latter nozzle in a concentrated stream coaxial with the latter nozzle. In addition, the air issuing from the air nozzle 16 also acts (after the manner of fluid issuing from the inner tube of an injector) for sucking 40 the mixture of air and material out of the entire upper portion of the receptacle, and for preventing the lifted material from collecting in or near the outlet bore.

To facilitate the directing of the agitated and 45 aerated material toward the discharge nozzle, we form the cover 3 so that its lower face is generally dome-shaped, with the highest point of the dome between the rear end of the discharge nozzle 8 and the vertical axis A of the jar. Then 50 we also have this lower face of the cap slope downward rearwardly (at opposite sides of the air nozzle 16 and of the cap part 3B into which this air nozzle is threaded) approximately to the level of the mouth end of the jar, as shown by the 55 dotted line 15 in Fig. 1, thereby enabling the said suction to act effectively also on material which has been forced upwardly in the rearward portion of the jar, so as to guide the lifted material to the discharge nozzle. 60

To obtain both an efficient suction and a forcible projection of the material after the latter is ejected through the discharge nozzle, we effectively elongate the horizontal air duct 4A by screwing into the cover (in axial alignment with 65 this duct) an air nozzle 16 which has a contracted outlet, and which has the discharge end of this outlet disposed forwardly of the vertical axis of the receptacle. Then we also provide an ample spacing between the tip of the air nozzle 70 16 and the rearward portion 8B of the bore of the discharge nozzle, so that the commingled air and material can flow freely through the discharge bore. To aid in this while still permitting the forward portion 8A of the bore of the discharge 75

nozzle to project the air and material in the form of a fairly concentrated spray 17, we desirably form this forward bore portion approximately cylindrical and make the rearward bore portion 5 8B of a decided forward taper.

As here shown, the main air valve comprises a tubular valve body 17 (Fig. 5) threaded axially into the upper end of the tubular handle 5 and having an annular shoulder 18 seated on a corresponding interior shoulder 19 in the handle. A cross-bore 20 extends through the valve body above this shoulder and at approximately the height of the horizontal air duct 4A, and this cross-bore opens at both ends into a peripheral 10 groove 21 in the valve body to permit air to flow from the cross-bore to the said air duct regardless of the rotational position of the valve body.

Slidably guided and extending through the axial bore of the valve body is a valve stem which 15 has a closure element 22 fastened to its lower end and which has at its upper end the finger-piece F, a compression spring 23 being interposed between this finger-piece and the valve body for continually urging the just described main valve 20 member upwardly to its closure position.

With our appliance thus constructed, and with both of the valve cocks 11 and 14 partly opened, the user can readily see experimentally (when the main valve is also opened) how far the material 25 is ejected from the container and to what degree this material is distributed by the air. Then he can readily adjust one or both of the valve members 11 and 14 according to the specific gravity of the material, the nature of the 30 material and the proportionate aeration desired. And, since the entire supply of air is controlled by the spring resisted main valve, this adjustment remains undisturbed whenever the spraying of the material is halted.

40 In practice, the providing of two separate adjustments for the supply of agitating and lifting air to the receptacle, and for the control of the air jet issuing from the air nozzle 16, is important for two reasons: One is the difference in the 45 amount of air required for agitating the material, which varies with the nature of the material, and another is the difference in the relative proportions of the emitted air to the ejected material, which may vary both with the material and with 50 the purpose for which the appliance is used. For example, the difference in the specific gravity between finely ground wool or rayon and vitreous enamel is enormous, thereby requiring relatively much more air for properly agitating the 55 heavier vitreous material within the receptacle.

So also, the relative amount of air emitted from one appliance needs to be adjusted for efficiently spraying many materials. For example, in distributing fine ground vitreous enamel over 60 the surface of a hot steel plate, upon which plate this material is afterward fused into an enamel coating, an undue amount of air would chill the metal so as to spoil the resulting coating. For that reason, the heretofore available appliance 65 for spraying finely divided materials have not proven feasible in the manufacture of enameled signs and the like, but our present invention entirely overcomes this difficulty and enables manufacturers of such signs to apply the vitreous 70 enamel with a simple spray device instead of using a sifting operation which is less economical in practice.

On the other hand, when a sheet of cloth or paper is to be coated with a thin layer of so-called 75 "flock" (meaning finely ground wool, cotton or

rayon), this can speedily be done by spraying such flock upon the sheet while the sheet is coated with still sticky varnish, then as soon as the entire surface of the sheet is covered with the flock, the air valve 14 can be closed, thereby 5 permitting air alone to issue from the appliance for expediting the hardening of the coating.

However, when the coating material is of such a nature that the particles will not readily pack or jam in the discharge outlet, the forward valve 10 11 can be kept closed during the spraying, thereby by enabling the air admitted to the receptacle to effect the entire ejection of the material in the form of a less concentrated mass spray and to a shorter distance from the appliance. 15

Since the body member of our appliance can be of aluminum, our entire appliance (including the receptacle) can readily be made sufficiently light so as to be manipulated by a user grasping the handle with one hand, and a mere unscrewing 20 of the receptacle permits instant access to its interior for refilling. Moreover, it will be obvious that all parts can readily be detached and cleaned when this becomes necessary.

However, while we have heretofore described 25 our solid-material spraying appliance having two separate controls in addition to a main air control valve, we do not wish to be limited in this respect. Nor do we wish to be limited to the above described details of construction and arrangement, since many changes might be made without departing either from the spirit of our invention or from the appended claims. 30

For example, if our appliance is to be used only 35 in connection with materials which do not require a relatively large amount of air for agitating, lifting and ejecting the material, the previously described valve for controlling the part of the air supply which is emitted through the air nozzle 16 can be omitted, as shown in the more 40 simple embodiment of Figs. 6 to 9. In this cheaper type, the upright bore into which the valve member 11 (which controls the air ejected into the receptacle) has its axis offset laterally from that of the air duct 4A, and the upright 45 bore is continued downward entirely through the cover by a smaller diameter bore 24 through which a portion of the air enters the interior of the receptacle 1.

On the other hand, we have found that for 50 some purposes our appliance can be used more advantageously if designed for projecting the material in a mass spray which is flattened in cross-section, and we have also found that the extent of this spray-shape flattening (which may 55 vary from an ellipse to an almost rectangular section) may need to be varied according to the nature of the material which is being sprayed. To meet these requirements, we also provide an auxiliary air-passage in the container-cap portion 60 of the body member of our appliance, provide an outlet nozzle having forwardly converging air discharge ports at opposite sides of a common outlet for the material and air issuing from the container, and provide separate means 65 for controlling the supply of air through the said auxiliary air-passage to the said discharge ports.

Thus, Fig. 10 shows the cap 3A of our appliance as provided, in addition to the air inlet passage 4B which leads to the air nozzle 16, with an auxiliary air-passage 30 opening into an annular groove 31 formed in the forwardly facing edge of the cap which has the outlet bore 6A. This outlet bore 6A is cylindrical and unthreaded 75

and slidably receives the shank 32 of an outlet nozzle which has its forward portion formed (after the manner of the air nozzles in spray guns) with two diametrically opposite and forwardly extending projections 33.

Each of these projections has an elbow-shaped air passage extending through it, with the rearward portion 34 of the passage open to the groove 31 and the forward portions 34A converging forwardly toward each other.

Then we provide an upright valve member 35 controlling a port 36 which connects the main air passage 4B with the auxiliary air passage 30, and dispose the other two adjustment-control valve members 11 and 14 as employed for the same purposes in the embodiment of Fig. 1, as shown in Fig. 10 which figure has the port 24 indicated in dotted lines. Thus arranged, the valve member 14 controls the flow of air through the downwardly leading passage 24 to the interior of the container, and the valve member 15 controls the supply of air to the air nozzle 16.

With this four-valve form of our appliance (which would also include a main air control valve 22 as shown in Fig. 1), the forwardly tapering inner portion 8B and the discharge portion 8A of the outlet for the discharge of the mixture of air and material can be the same as shown in Fig. 1; and when the valve 35 is closed, the material is discharged in the form of an aerated conical mass spray.

However, when the valve 35 is also opened, the supplemental air jets issuing from the ports 34A will flatten the projected spray so as to change the cross-section of the spray to that of an ellipsis having its major axis at right angles to the common plane of the axes of the forwardly converging supplemental air jets. By varying the extent to which the supplemental air-control valve 35 is opened, we can correspondingly vary the extent to which the emitted spray of material is flattened, so as to change the cross-section of this spray all the way from a circle to a highly elongated and almost bar-like contour.

With the discharge nozzle positioned as shown in Fig. 10, the flattened spray would have its major axis in a horizontal plane diametric of the axis A of the said discharge nozzle, but for some purposes it may be more advantageous to have the discharge spray flattened along an upright plane so as to be projected substantially in the form of an upright sheet which will move laterally over an upright surface when the operator passes the appliance horizontally in front of this surface.

To permit this, we desirably construct the discharge nozzle so that its (rearward) unthreaded shank sockets slidably in the cap bore 6A, and so that this nozzle presents a flat annular rear face bearing flatwise against the adjacent part of the frontal cap portion of the body member of our appliance, and clamp this discharge nozzle to the body member by a clamping ring 38 as shown in Fig. 10.

By slightly loosening the ring 38, the user can speedily rotate the discharge nozzle so as to have the spray flattened along any desired plane diametric of the axis of the nozzle, and can then tighten the ring to hold the nozzle in its adjusted position.

With the four valves thus disposed, the inlet-controlling valve member F turns the air supply off and on. The horizontal valve members 14 and 15 respectively control the proportional supply

of air to the interior of the container and to the air nozzle 16, and the upright valve 35 controls the air supply to the groove 31 and from this groove to the ports 34A from which the spray-flattening air jets issue. With the upright valve 35 closed, this type of our appliance operates in the same manner as the previously described two embodiments.

With the valve 35 opened also, the emitted spray is flattened to depending both on the extent to which that valve is opened and also on the extent to which the horizontal nozzle-air controlling valve 16 is opened. Consequently, the user can readily adjust the valve 14 for admitting air to the container according to the nature of the material in the container, adjust the valve 15 for securing a projection of the material to the desired distance, and adjust the valve 35 for flattening the emitted spray to any desired extent. By making the groove 31 of a cross-section many times greater than that of the auxiliary air passage 30, we permit the air pressure to equalize throughout the interior of this groove, thereby obtaining air jets of equal velocity and volume from both of the supplemental air ports 34A.

By arranging the outlet nozzle so that it can easily be rotated when the clamping ring 38 is slightly loosened, we enable our appliance, when held substantially upright by the user, to project the material in a spray flattened along any desired plane diametric of the axis A of that outlet nozzle, so that the embodiment of Figs. 10 to 12 readily lends itself to the projecting of an enormous variety of finely divided solid materials—as for example, paper scraps for filling hollow walls to deaden sound, sawdust for producing a rough finish on a wall coated with a still wet varnish or other adhesive material, sugar for coating cakes, or textile flock for coating book covers or caskets.

With each of the illustrated embodiments, the air nozzle 16 desirably has a polygonal enlargement 16B intermediate of its length, for engagement by a wrench when assembling the appliance. This also enables the user to vary the spacing of the tip of the air nozzle from the discharge bore 8A, so as to effect an adjustment of the concentration of the ejected conical mass spray, and a similar adjustment might be made with the air nozzle in the triple-valve spray device of Fig. 1.

So also, the distance to which the air pipe 13 extends downwardly into the receptacle in Fig. 1 may be varied, and even the position of the outlet of this pipe with respect to the axis of the receptacle. However, we have found our appliance to operate most efficiently when the air is admitted to the receptacle considerably rearward of the receptacle axis (when the discharge outlet is at the front) and so as to emit the air approximately vertically downward. Then when the appliance is in use, some of the material will also be swirled upwards along (or near) most of the riser side portions of the receptacle in addition to the material following the general direction of the dotted line J in Fig. 1, as for example along the dotted line 26. Consequently, the entire dome-like lower face of the cover 3 excepting that underhanging the nozzle-receiving portion 3B redirects the air-lifted material toward the entrance portion 8B of the discharge outlet, thereby substantially equalizing the distribution of the material and air in the discharged mixture.

In both of the illustrated embodiments of our invention, the compressed air which is directed

downwardly into the receptacle issues from an outlet disposed above the midheight of the receptacle—or above the material when the receptacle is not more than half filled initially—serves 5 primarily for agitating and lifting the upper portion of the material, while the forcible projecting of the lifted material out of the receptacle is effected by the air which issues from the air nozzle 16 and which is directed coaxially with the outlet 16 and which is directed coaxially with the outlet 8. Moreover, by forming the cover of the receptacle so that it arches freely above the forward portion of the air nozzle 16, we permit the particles of material to be lifted freely above and alongside this forward air nozzle portion, as 10 well as in front of the said nozzle, and we utilize the suction effect of the air issuing from the air nozzle 16 for directing the lifted material into the discharge nozzle 8.

Consequently, our invention avoids the following five difficulties encountered in attempts at 20 using heretofore proposed pneumatic appliances for spraying finely divided materials:

(1) The substantial choking of the downwardly directed air duct which occurs when this duct 25 opens near the bottom of the receptacle, so that the outlet end of this duct is imbedded in the material unless the receptacle is almost empty.

(2) The impossibility of projecting the material either for any substantial distance or in a 30 well concentrated stream, which occurs when the appliance is so constructed that the material is discharged only by the residual force left in the air after this air has agitated and lifted the material.

(3) The reducing of the discharge velocity of the ejected material, which occurs when the downwardly issuing air is directed against the inner face of a riser wall of the receptacle (instead of being directed toward the bottom of the 40 receptacle as in our here presented appliance) so that this air is reduced in velocity before it reaches the material.

(4) The reduction in the concentration of the effected discharge of material which occurs when 45 the air nozzle which opens toward the material discharge outlet at the front of the appliance has its outlet rearward of the vertical axis of the receptacle, or has this outlet out of alinement with the said material discharge outlet.

(5) A lack of uniformity as to the distribution 50 of the material in the projected spray.

Moreover, while we have illustrated our invention in the form of light and portable appliances, we do not wish to be limited in this respect. Indeed, even with a relatively small form of our appliance including a flat-bottomed receptacle, we desirably provide the cover with an upwardly directed hook 25 (as in Figs. 1, 2 and 3) so that this appliance can be suspended by a cord or the like which will then support the weight of the entire appliance while permitting the user to vary the direction of emitted spray.

We claim as our invention:

1. A pneumatic appliance for spraying comminuted solid materials, comprising an upright receptacle; a detachable cover normally sealed to the mouth of the receptacle, the cover having a horizontal bore at its forward edge and above the mouth of the receptacle; a discharge nozzle 65 mounted in the said bore; the cover having the major portion of its lower face of a dome shape with the highest portion of the dome spaced rearwardly from the discharge nozzle and forwardly from the axis of the receptacle, and having a forward portion of the said lower face sloping for-

wardly downward and substantially merging with the rear end of the bore of the discharge nozzle; the cover having a horizontal air passage extending through the rearward portion coaxial with the said nozzle, the said passage having its forward end open and freely spaced rearwardly from both the discharge nozzle and freely underhanging the cover and disposed forwardly of the axis of the receptacle; the cover also having a port leading downwardly from the said passage behind the said receptacle axis and opening into the receptacle; and means for supplying compressed air to the rear end of the said passage; the air duct having its forward end spaced rearwardly from the said nozzle and farther forward than the said highest portion of the dome-shaped lower face of the cover. 10 15

2. An appliance for spraying finely divided solid material, comprising an upright container for the material, the container having a lateral discharge outlet adjacent its forward upper edge; means for projecting an initially cylindrical jet of compressed air downwardly and in an approximately vertical direction into the container with the axis of the jet spaced rearwardly from the 25 axis of the container, and with the discharge of the said jet starting above the midheight of the container whereby the said air jet agitates the material and lifts the material, means for projecting a second jet of air across the upper portion of the container coaxial with the said opening, and adjustable means for proportioning the air supply to the said two projecting means, the second air projecting means including an air nozzle threaded into the cover and having its 30 35 outlet disposed forwardly of the vertical axis of the receptacle and spaced rearwardly from the discharge outlet of the container, the said air nozzle being freely spaced downwardly from the top of the container. 40

3. A pneumatic appliance for spraying comminuted dry material housed by an upright receptacle, comprising a receptacle cover provided at its forward edge with an aperture and having an annular groove in the said forward edge concentric with the said aperture; the cover also having a main air duct extending forwardly into it and presenting its discharge end coaxial with and spaced rearwardly from the said apertured cover edge, an air port leading downwardly from the main air duct and opening into the container, and an auxiliary air passage leading to the said groove from a part of the main air duct rearwardly of the connection of that duct to the said downwardly leading air port; an air nozzle 50 55 mounted on the cover and provided with a central air discharge port alining with the said aperture and with a supplemental air port leading forwardly from the said groove; and separately adjustable valves respectively controlling the supply of air from the main air duct to the 60 said downwardly leading air port, the discharge end of the main air duct, and the auxiliary air passage.

4. A pneumatic appliance for spraying comminuted dry material, comprising an upright receptacle housing the material, a receptacle cover provided at its forward edge with an outlet bore above the mouth of the receptacle, means supported by the cover and freely spaced rearwardly from the rear end of the said outlet for projecting air forwardly and coaxial with the said outlet bore in a jet freely spaced downwardly from the forward portion of the cover and thereafter axially through the outlet to produce a suction from the upper portion of the receptacle 65 70 75

- through the outlet; means for projecting air downwardly into the receptacle from a point lower than axis of the said outlet and above the midheight of the receptacle, so as to agitate material and air within the receptacle, means for supplying compressed air to both of the said air-projecting means, and adjustable means for proportioning the amount of air supplied to the said two air-projecting means; the means for projecting air downwardly being constructed to project air in a jet the initial diameter of which is a minor fraction of the diameter of the said outlet bore.
5. A material spraying appliance as per claim 4, in which the lower face of the cover is substantially dome-shaped and arches freely above the forward portion of the first named air projecting means, and in which the forward portion of the said face slopes downward and into merging relation to the rear end of the said outlet for guiding material from the uppermost portion of the receptacle outlet.
10. A pneumatic appliance for spraying dry comminuted material, comprising an upright receptacle housing the material; a cover member fitted upon the mouth end of the receptacle and provided at its forward edge with a discharge bore; the cover member having an air passage extending into it and presenting its outlet portion coaxial with the said discharge bore and spaced rearwardly from the rear end of the said discharge bore; the diameter of the outlet end of the said air passage being a minor fraction of the diameter of the rear end of the discharge bore; the cover member also being provided with a second air passage for projecting air downwardly into the receptacle in a jet of smaller diameter than the rear end of the said discharge bore.
15. A pneumatic material spraying appliance as per claim 6, in which the rearward portion of the lower face of the cover member is formed for forwardly deflecting toward the said outlet the material lifted in the receptacle through the action of the air projected from the said second air passage, and for permitting the lifted material to flow around the air issuing from the first named air passage.
20. A pneumatic material spraying appliance as per claim 6, including valve means on the cover member for proportioning the amount of air projected respectively from the said air passage and from the said air duct.
25. A pneumatic appliance for spraying comminuted dry material, comprising an upright receptacle housing the material, a receptacle cover provided at its forward edge with an outlet bore above the mouth of the receptacle; the cover also being provided with an air passage having its outlet portion underhanging and freely spaced downwardly from a forward portion of the cover, the outlet portion of the said passage being coaxial with and spaced rearwardly from the said outlet bore and being of smaller diameter than the rear end of the said outlet bore; and an air duct supported by the cover and disposed for directing air downwardly against material in the container, the said duct presenting its outlet end above the midheight of the receptacle.
30. A material spraying appliance as per claim 6, in which the outlet bore has its rearward portion flaring rearwardly, and in which the lower face of the cover member has the general shape of a dome having its highest portion between the outlet bore of the cover and the vertical axis of the receptacle, the said dome-shaped face sloping forwardly downward approximately to the rear end of the said outlet bore and rearwardly to the mouth end of the receptacle.
35. A spray gun for fibrous material including a receptacle having a relatively large open neck, a gun body mounted on said neck overlying the opening of said receptacle, said gun body having a main air passage adapted to communicate with a source of air pressure, means closing said passage manually operable to open the same, said gun body having an orifice communicating with said main air passage and having its discharge directed into said receptacle for agitating said material, means to regulate the air flow in said orifice, a spray head carried by said gun body having a central nozzle opening with a forwardly convergent surface providing a discharge throat, and oppositely disposed side openings, said main air passage being of lesser diameter than said discharge throat, said gun body having an auxiliary air passage communicating with said main air passage and said side openings whereby the stream of fibrous material passing from said nozzle opening is caused to be divergent in a single plane and means to regulate the flow of air through said side openings.
40. A pneumatic appliance for spraying comminuted dry material, comprising an upright receptacle housing the material, a receptacle cover provided at its forward edge with an outlet bore above the mouth of the receptacle; the cover also being provided with an air passage having its outlet portion underhanging and freely spaced downwardly from a forward portion of the cover, the outlet portion of the said passage being coaxial with and spaced rearwardly from the said outlet bore and being of smaller diameter than the rear end of the said outlet bore; and an air tube supported by the cover and communicating with said air passage and disposed for directing air downwardly against material in the receptacle.
45. A pneumatic appliance for spraying dry comminuted material, comprising an upright receptacle housing the material; a cover member fitted upon the mouth end of the receptacle and having a lateral aperture; a material discharge nozzle fitted upon and detachable from the apertured portion of the cover member, the cover member having a main air passage extending into it; and an air projecting nozzle detachably fastened to the cover member and connected to the main air passage and coaxial with the said discharge nozzle, the discharge end of the air projecting nozzle being freely spaced from the bore of the discharge nozzle; the cover member also having a supplemental air passage disposed for projecting air downward into the receptacle to agitate and lift material within the receptacle, and the cover member having a downward face portion thereof spaced upwardly from the air projecting nozzle and from the inlet end of the bore of the discharge nozzle to permit both air and lifted material to pass alongside and above the air projecting nozzle.
50. A pneumatic appliance as per claim 13, in which the said downward face portion of the cover is substantially dome-shaped and merges with the inlet end of the said aperture.
55. A pneumatic appliance as per claim 13, including a valve controlling the entire air supply to both of the said air passages, and an auxiliary valve controlling the supply of air to the supplemental air passage.
60. A pneumatic appliance for spraying dry

comminuted material, comprising an upright receptacle housing the material; a cover member fitted upon the mouth end of the receptacle and having a lateral aperture; a material discharge 5 nozzle fitted upon and detachable from the apertured portion of the cover member, the cover member having a main air passage extending into it; an air projecting nozzle detachably fastened to the cover member and connected to the main 10 air passage and coaxial with the said discharge nozzle, the discharge end of the air projecting nozzle being freely spaced from the bore of the discharge nozzle; the cover member also having a supplemental air passage disposed for projecting 15 air downward into the receptacle to agitate and lift material within the receptacle; an exterior air nozzle associated with the material nozzle,

the cover having a third air passage leading to the said exterior nozzle, and the exterior air nozzle having outlet ports for projecting forwardly converging air jets against the stream of material and air issuing from the material nozzle. 5

17. A pneumatic appliance as per claim 16, in which the supplemental air passage and the third air passage both lead from a part of the main air passage rearward of the connection of the latter to the air projecting nozzle; the appliance also 10 including separate valves for controlling the flow of air through the supplemental air passage, and for controlling the supply of air to the said outlet ports of the air nozzle.
